(57) **CLAIM**

We claim the ornamental design for a luminous device for a vehicle, as shown and described.

DESCRIPTION

FIG. 1 is a top view of the luminous device for a vehicle;
FIG. 2 is a back view of the luminous device for a vehicle;
FIG. 3 is a bottom view of the luminous device for a vehicle;
FIG. 4 is a front view of the luminous device for a vehicle;
FIG. 5 is a right side view of the luminous device for a vehicle;
FIG. 6 is a left side view of the luminous device for a vehicle;
and,
FIG. 7 is a perspective view of luminous device for a vehicle.
